UNITED STATES PATENT OFFICE.

JAMES LARSON, OF CHICAGO, ILLINOIS.

MOP-HOLDER.

No. 839,006.

Specification of Letters Patent.

Patented Dec. 18, 1906.

Application filed June 15, 1906. Serial No. 321,860.

To all whom it may concern:

Be it known that I, JAMES LARSON, a citizen of the United States, residing at Chicago, in the county of Cook and State of Illinois, have invented a new and useful Mop-Holder, of which the following is a specification.

My invention relates to an improvement in mop-holders in which a cloth, sponge, or other soft material is used for cleaning wood-work, windows, &c.; and the object of my improvement is to provide a mop-holder in which the mop can be easily removed and cleaned and in which a sponge or other soft material for cleaning windows, woodwork, and floors can be easily and quickly fastened in it for use where the work cannot be reached readily by hand. I attain these objects by the mechanism illustrated in the accompanying drawings, in which—

Figure 1 is a perspective view of the entire mop-holder with a cloth attached in it. Fig. 2 is an end view of the mop-head when open.

Two blocks of wood or other suitable material concave on their inner faces constitute the jaws, held together by hinges at the edges, as shown, Fig. 1, *a a*. The clasp is made of hard wire and formed with a spring at each end, as shown, Fig. 1, *b b*, which serves also for a hold on putting in or taking off the

clasp, and also allows the clasp to widen as 30 it is forced down over the inclined jaws and holds the material placed in the mop-holder with a firm and elastic grip. The handle is attached to one of the jaws near the side from which the jaws open, so as to give room 35 for moving the clasp down over the jaws until it gets sufficient pressure to hold the mop. The handle being thus placed close to the operating part of the mop insures greater durability and strength to the mop- 40 holder.

What I claim as my invention, and desire to secure by Letters Patent, is—

The combination in a mop-holder of two blocks hinged together at one edge, shaped 45 concave on their inner faces to allow a better grip on the mop, a clasp slidably engaging the outer faces of said blocks and formed with a spring-coil at each end substantially as described.

In testimony whereof I have signed my name to this specification in the presence of two subscribing witnesses.

JAMES LARSON.
